UNITED STATES PATENT OFFICE.

THERON L. ARNOLD AND FRANK E. BROWN, OF THREE RIVERS, MICHIGAN.

PREPAYMENT ATTACHMENT FOR ELECTRIC METERS.

SPECIFICATION forming part of Letters Patent No. 728,531, dated May 19, 1903.

Application filed July 21, 1902. Serial No. 116,419. (No model.)

To all whom it may concern:

Be it known that we, THERON L. ARNOLD and FRANK E. BROWN, citizens of the United States, and residents of Three Rivers, in the county of St. Joseph, State of Michigan, have jointly invented new and useful Improvements in Prepaying Attachments for Electric Meters, of which the following is a specification.

- 10 The object of this invention is to construct the improvements hereinafter described and claimed in an apparatus for attachment to and use in connection with any registering-meter which measures electrical current, whereby 15 electric-light consumers are compelled to prepay into the apparatus the cost of the light for a greater or less period, optional with them, before the electric current which produces the light is supplied and said supply 20 ceasing at the instant they have consumed all the electricity they have paid for unless they make further payment before the light fails to burn.

The construction and manipulation of our 25 prepaying attachment is such that a visible register of the amount of electric current being used is made, so that the users of electric lights by looking at a dial provided for the purpose may know exactly how they stand, 30 and thus be warned when to make further payment to prevent a failure at any time of the lights burning.

In the drawings forming a part of this specification, Figure 1 is a front elevation of our 35 prepaying attachment and also a front elevation of an ordinary electric meter for measuring the current and to which our invention is designed as an attachment. Fig. 2 is the same, the front wall of our attachment being 40 removed and a portion of the meter being broken away and a portion of its front wall removed; Fig. 3, an enlarged section in Fig. 2 on dotted line *h h*, looking from a point at the right; Fig. 4, a sectional elevation, enlarged, on dotted line *e e* in Fig. 5, looking 45 from a point at the left, certain parts being broken; and Fig. 4 is also a section in part on dotted lines *c c* in Fig. 1 and *s s* in Fig. 2, looking from a point at the right; Fig. 5, a 50 sectional elevation on dotted line *u u* in Fig. 4, looking from a point at the right and showing the gears in dotted lines; Fig. 6, an en-

larged broken portion of the clutch-gears in Fig. 4, their shaft being in section on dotted line *v v*, looking from a point at the left; 55 Fig. 7, an enlarged broken view of the escapement-wheel in Fig. 4 with its shaft in section on dotted line *w w*, looking from a point at the left; Fig. 8, an enlarged vertical section of the escapement-wheel and escapement in 60 Figs. 4 and 5, the view being taken on dotted line *z z* in Fig. 5, looking from a point at the right, and on line *x x* in Fig. 7; and Fig. 9 is a section on dotted line *i i* in Fig. 4, looking from above, and on sectional line *o o* in Fig. 65 8, looking from above.

Referring to the parts of the drawings pointed out by numerals, 12 shows the ordinary meter in common use for measuring electric current. Their operation is well understood and needs no lengthy description. Suffice it to say that the circuit-wires 13 and 70 14 carry the electric current from the main into and out of the meter 12 in Fig. 1 and that the registering-hands of the dials are operated by said current in the regular way, transmitting the register of the unit-dial 15 onto the other dials 16 in the increasing scale. 75

Our prepaying attachment or its apparatus is contained in a metal case 17, Fig. 1, designed for attachment to the wall of a room in some convenient location. The case is provided with a door 18. It may have a lock of a private nature and the collector do the collecting at stated intervals. The hand of the 85 dial 15 is removed from its shaft 19 or journal, and a disk 20, of fiber or suitable insulating material and provided with a hub 21, is fitted on said journal 19. This is shown in Fig. 2, the meter portion of which is enlarged 90 from Fig. 1 and a portion of the front wall removed, disclosing the disk 20 in place. On the hub 21 is a thimble 22, made of copper or other conducting material, and is behind the disk 20. A circuit-terminal 23, of like conducting material as the thimble and attached to the same integrally or otherwise, extends radially from the hub 21 in the rear of the disk 20 and passes through it and projecting a little beyond its front face, as in Fig. 3. A 100 little removed from the end of this circuit-terminal 23, toward the periphery of the disk 20, is a pin 24, projecting outward like the end of the circuit-terminal 23. Three circuit-

wires enter the case of this meter at the upper right-hand side, Figs. 1 and 2, and constituting terminals 25, 26, and 27, which are delicately elastic. The upper terminal 25 first contacts with the pin 24 and when the disk 20 revolves snaps off into contact with the circuit-terminal 23, closing the electric circuit with the terminal 26, and a like action takes place in relation to the circuit-terminal 27 when the disk 20 revolves thus far. The purpose is to make a quick break of the circuit and prevent sparks burning the terminals 25 and 27. The circuit-terminal 26 rests on the thimble 22 in a manner similar to brush-

wires in electrical apparatuses. The disk 20 is of course revolved the same as would have been the disk 15 or what is termed the "register unit-dial" on shaft 19. Hence twice in its revolution the terminal 23 contacts to close circuit. The operation of the invention causes a register by the hand 30 on the dial 28 of the electric current which is being consumed by the lights at 29.

Through the front wall of the case 17, Fig. 1, is a slot 31, into which to insert dimes, a slot 32 for quarter-dollars, and a slot 33 for half-dollars. They are of a correct size for the purpose, and the proper piece of money must go in its proper slot, thus fixing the starting-point of the carrier according to the amount of money paid in, from which point the coin-carrier is swung, with its particular piece of coin, to a given place 35 in Fig. 5 for delivering the coin off from the end of the curved floor 41, when said coin falls to the bottom of the case 17, likely in some receptacle placed there to receive it. This movement of the coin-carrier 34 causes the weight 36 to rise a distance according to the amount of payment, since the after-lowering of said weight operates the circuit-maker 37, Figs. 2, 4, and 5, to stop the supply of the electric current. This will be further explained and finally made definite and clear in the description of the operation. Within the case 17 and in proper position for these slots 31, 32, and 33 is the coin-carrier 34, hung on a journal 38, and also attached to the back plate 43 by brackets 105 and 106, Figs. 4 and 5. The journal is supposed to have bearings in the front wall of the case 17, and to this end of said journal, outside of the wall of said case, is attached the thumb-wheel 51. The right-hand end of said journal 38 is loosely passed onto the end of the journal 40, which projects through the wall 60, the opposite end of the journal 40 having bearings in the wall 50, Fig. 4. It may be here stated that rest of the journals bearing-gears hereinafter referred to have bearings or supports in said walls 50 and 60, the latter wall being dotted in Fig. 5. The coin-carrier 34 is of a size to receive the coins edgewise and to retain them in said position until they are delivered off from the end of the curved floor 41 at 35 from the end of the open bottom of said coin-carrier, Fig. 5. This curved floor 41 is attached to

the inside of the front wall of the case 17 by a bracket 42 and serves to retain the coin in the coin-carrier 34 until delivered off its end 70 at 35, as explained. The coin-carrier being attached to the back plate 43 and said plate being attached to the journal 38, said back plate when the journal is revolved swings between the inner face of the front wall of 75 the case 17 and the contiguous edge of the curved floor 41. During this operation the coin-carrier 34 of course swings, and the peculiar construction holds and steadies said carrier and forms a good guide to its move- 80

In Fig. 4 the side wall of the coin-carrier 34 is broken away and discloses an interlocking lever 46 for engaging with the teeth 44 of the wheel 45 on shaft 40. In the coin-carrier 85 34 is also pivoted a push-lever 47, held swung back in its normal position by a spring 48. Attached to the interlocking lever 46 is a controlling - spring 49, resting against the push-lever 47.

In Fig. 4 is shown a dotted coin 61, which has been passed into the case 17 through one of the slots 31, 32, or 33, according to the value of said coin. Said coin of course passed into the coin-carrier, which had been swung 95 to the proper position to register with the particular slot. It should have been stated that a slot made through the back plate 43 registers with the open edge or mouth of the coin-carrier 34 and by turning the thumb-wheel 100 51 is made to register with the slots 31, 32, and 33 in the front wall of case 17. This will appear clear when it is understood that the edge of the coin-carrier 34 which is open and styled the "mouth" fits against the back plate 105 43 at the point where the slot through the back plate is located. The coin 61, referred to, having been inserted, as stated, the coin-carrier, by means of thumb - wheel 51, is 110 swung toward the right in Fig. 5 until the coin drops out at 35. When the coin 61 was inserted, it pushed out on the push-lever 47, and this in turn, through the spring 49, pushed out on the interlocking lever 46. The lower end 52 of the former, Figs. 4 and 5, 115 when the coin-carrier was rotated or swung to deposit the coin at 35, pushed the slide-bar 53, which in turn operated the swinging member 62 of the circuit-maker 37, bringing the surfaces 68 into contact, thus closing the circuit and establishing a supply of electric current to the lights 29, Fig. 1. During this action the lower end of the interlocking lever 46 engaged the teeth 44 of the wheel 45, and when the coin-carrier 34 was swung to 120 deliver the coin at 35 the wheel 45 was revolved and also the windlass 54 through the gears 55 on shaft 40, 56 on shaft 83, 57 on shaft 84, 58 on shaft 84, and 59 on shaft 85, said windlass being on the latter-named shaft, 125 and the cord 107 was wound up on its windlass, carrying up the weight 36 a given distance in accordance with the movement of the coin-carrier 34. The swinging member 130

62 of the circuit-maker 37 is pivoted at 63, Fig. 5, and when it was swung to bring this member against the fixed member 64 the projection 103 was disengaged from the nose 108 of the pivoted dog 65, bringing said nose against the end of the projection 103 and holding the members of the circuit-maker in contact to keep up the electric supply to the lights 29. The dog 65 is held to the position 10 shown in Fig. 5 with its nose engaging the projection and holding the members of the circuit-maker apart, the circuit thus being broken by the spring 66, attached to the pivot of the dog and bearing against its side, 15 as in Fig. 5.

The lower ends of the members of the circuit-maker 37 have conducting material 68 on their inner faces, from which lateral projections extend at 69, there being insulating material 70 between the inner and outer conducting material. The swinging member of the circuit-maker in Fig. 5 is on a vertical section.

The magnets 71 and 72 are shown near to 25 and a little below the toothed wheel 45 in Fig. 2. Above them is an armature 73, pivoted centrally on shaft 74. Attached to the armature are two brushes 75 and 76, the bar 77, connecting said brushes, being separated 30 from the armature by the insulation 78. The contact-posts for the brushes are shown at 79 and 80, Figs. 2 and 4. Rigidly attached to the shaft 74 is the downward extension of the escapement-operator 81, which oscillates when 35 the armature 73 teeters up and down on its pivot. This escapement 82 is pivoted at 86, Figs. 4 and 5, and when it is oscillated on its pivot first one end goes between the teeth of the escapement-wheel 87 and then the other 40 end. The escapement is shown broken away in Fig. 5, and the escapement-wheel 87 in this figure is shown dotted in. The upper end of the escapement-operator 81 is provided with an oblique slot 88, (especially shown in 45 Figs. 8 and 9,) into which slot the lower end of the escapement 82 is loosely inserted, by which means when the armature 73 teeters and the escapement-operator oscillates the weight 36 is allowed to lower or run down. 50 After the weight has been wound up by turning the thumb-wheel 51 and through the means before explained it is necessary that it shall not abnormally lower again, which it might do by its own weight. To this end the 55 gear 56 has attached to it a clutch-gear 90, and these two gears are loosely mounted on the shaft 83 in order that they will revolve on it when winding up the weight 36 and be prevented from revolving by the following 60 means in the opposite direction: A dog 91, spring-controlled, is attached to gear 92, said gear being rigidly attached to its revolvable shaft 83. The dog 91, Fig. 6, engages the teeth of the gear 90. By this means when 65 the armature through the escapement frees the escapement-wheel 87, Figs. 4, 7, and 8, the shaft 83 and its gears 56, 90, and 92 all re-

volve in said opposite direction, allowing the windlass 54 to unwind its cord 61 and lower the weight 36. When said weight is lowered 70 onto the pan 93, the latter tilts down, swinging the upright lever 94, which is attached to the pan-shaft 95, against the dog 65, which action releases the swinging member 62 of the circuit-maker 37, breaking the circuit and 75 putting out the lights. This lever 94 is shown broken in Fig. 4. It is desired that there be no slight motion or an abnormal vibration to the escapement-wheel 87, and to prevent this we have provided a dog 96, Figs. 4 and 6, having two downward prongs at the free end to engage the teeth of the gear 92, said dog being mounted pivotally on the shaft 97 and held to action by the spring 98 on shaft 97, Fig. 4, and it will yield from engagement 80 with the gear 92 when the weight 36 is running down.

The three electric circuits in use in carrying into effect our invention are traced as follows: The lights 29 and also the old mechanism in the meter 12 are supplied with the current over wire 13 from the mains or supply, said wire 13 being shown as entering the meter 12 at the lower left-hand corner of Fig. 1, from thence out at the lower right-hand corner of meter 12 and on into the case 17 of our prepaying attachment, through the circuit-maker 37, on over wire 13 to lights 29, thence back over wire 14 to the electric supply. The circuit the current of which operates to pull down the right-hand end of the armature 73, and thus tilt the escapement 82 and allow the escapement-wheel to jog and let the weight 36 lower, is over the circuit-terminal 25 within the meter 12, thence out 90 and on over wire 100 into the case 17, to magnet 72, thence over wire 100 to contact-post 79, electric brush 75, thence on over wire 100 through the circuit-maker 37, thence over wire 13 to lights 29, and back over wires 14 100 101, circuit-terminal 26, thimble 22, circuit-terminal 23, to circuit-terminal 25, the point of starting. The circuit the current of which causes the other end of the armature 73 to fall and to act in the same manner on the escapement 82 is over circuit-terminal 27 in the old meter 12, out over wire 102 into the case 17, and on over wire 102 to magnet 71, thence over wire 102 to contact-post 80, thence over electric brush 76, wire 100, through circuit-maker 37, and on over wire 13 to the lights 29 and back over wires 14 101, circuit-terminal 26, thimble 22, circuit-terminal 27, point of starting.

In the operation the customer grasps the 125 thumb-wheel 51 and sets the coin-carrier so that the entrance through the back plate 43 registers with the particular slot through the front wall of case 17 that he desires to enter his coin. After the coin is inserted he oscillates the coin-carrier to deposit the coin at 130 35, as stated. If the circuit-maker 37 is open, as in Fig. 5, the angled end 52 of the push-lever 47 will move the sliding bar 53

and close the circuit-maker, and thus furnish electric current to the lights. If the circuit-maker had been closed, payment could be made in advance, if desired. As before stated 5 in the description, when the circuit-maker is closed by the action of the sliding bar 53 the projection 103 is drawn away from beneath the nose 108 of the dog 65 and the spring 66 tilts the body of the dog a little to 10 the left, which tilts the nose 108 down where the end of its nose abuts against the end of the projection 103 and locks or holds the circuit closed until the dog 65 is again tripped by the action of the lever 94 when the weight 15 has again tilted the pan 93. When the later action takes place, the nose 108 is raised and the member 62 swings to the left, carrying its projection 103 beneath the nose 108, the latter of which is held in contact with said 20 projection 103 by the tension of the spring 66, thus holding the member 62 in this position until the sliding bar 53 is again operated by the rotation of the coin-carrier. Since the insertion of the coin 61 caused the lower 25 end of the interlocking lever 46 to engage the teeth 44 of the wheel 45, it follows that when the coin-carrier was oscillated to deliver the coin at 35 the windlass wound up the cord 107 and raised the weight such a distance as cor- 30 responded with the amount of current paid for—that is, the same distance as the consumption of said amount of current would lower said weight. It is of course understood that the action of the current on the 35 old meter 12 is the same as prior to the attachment of our invention in making the register on dials 16; but no visible register can appear on the dial 15 removed, the disk 20 now revolving as was said disk 15. When- 40 ever contact of circuit-terminals 23 and 25 takes place, the magnet 72 is energized and draws down its end of the armature 73, thus operating the escapement 82 and lowering the weight a little. When contact of the cir- 45 cuit-terminals, as the disk 20 keeps revolving, (marked 23 and 27,) takes place, the mag- net 71 is energized and draws down its end of the armature 73, the other end of said ar- mature rising, and again the escapement 82 50 operates and the weight lowers a little, and so on until the weight 36 tilts the pan 93 and closes the circuit-maker 37, shutting off the lights, as before explained. The consumer need not wait until the lights go out, but 55 may keep paying in coins now and then, since the dial 28 registers how he stands.

Having thus described our invention, what we claim as new, and desire to secure by Letters Patent of the United States of America, is—

60

1. In a prepaying attachment for electric meters, the coin-carrier adapted to be rotated or swung, a pivoted spring-controlled push-lever therein adapted to be pushed out by the insertion of a coin, suitable circuits, a 65 circuit-maker consisting of a fixed member, and a swinging member, the latter being pro- vided with a projection, a pivoted spring- actuated dog provided with the nose for co- acting with the projection of the swinging 70 member, the sliding bar adapted to be forced against the swinging member to close the cir- cuit, the pan pendent from a pivotal shaft, an upright lever mounted on said shaft for tripping the dog, and a weight adapted to 75 lower as the electricity is consumed, and to finally tilt the pan when the electric light paid for has been used, all combined, substan- tially as set forth.

2. In a prepaying attachment for electric 80 meters, the coin-carrier adapted to be rotated or swung, the pivoted spring-controlled inter- locking lever therein adapted to be pushed out by the insertion of the coin, a toothed 85 wheel in position to be engaged by the end 90 of the interlocking lever when thus pushed out, and to be revolved when the coin-carrier is swung, a windlass, cord, and weight, con- necting shafts and gears, and clutch-gears be- 95 tween the toothed wheel and windlass, the escapement-operator adapted to be swung by the tilting of the armature and being pro- vided in the upper end with the oblique slot, the escapement-wheel on the shaft of the clutch-gears, the escapement the ends of which 100 are adapted to play in and out between the cogs of the escapement-wheel and its lower end being extended loose in the slot of the escapement-operator, and electrically-oper- ated means for operating the escapement-op- erator, all combined, whereby the weight is 105 raised and permitted to lower by the inde- pently-acting but connected mechanism, substantially as set forth.

In testimony of the foregoing we have here- 105 unto set our hands in the presence of two wit- nesses.
